ATTORNEY

UNITED STATES PATENT OFFICE.

ANDREW KROUSE, OF BRIDGEPORT, CONNECTICUT.

DESIGN FOR A SUPPORT FOR PINCUSHIONS.

SPECIFICATION forming part of Design No. 23,041, dated February 6, 1894.

Application filed December 28, 1893. Serial No. 495,010. Term of patent 3½ years.

To all whom it may concern:

Be it known that I, ANDREW KROUSE, a citizen of the United States, residing at Bridgeport, in the county of Fairfield and State of Connecticut, have invented and produced a new and original Design for Supports for Pincushions; and I do hereby declare the following to be a full, clear, and exact description of the invention, such as will enable others skilled in the art to which it appertains to make and use the same.

In the accompanying drawings which illustrate my design Figure 1 is a side elevation of the same, and Fig. 2 a front view.

The leading feature of my design is, the body or stand, in which the pin cushion proper is supported, shaped to represent an infant's knitted shoe, with a scalloped band

at the top of the shoe, and the representation of a ribbon around such band and tied at the front of the latter in a bow knot.

1 is the body or stand, 2 the scalloped band at the top thereof, 3 the ribbon around such band, 4 the bow knot into which such ribbon is tied at the front of the band, and 5 the cushion.

I claim—

The design for a support for pin cushions substantially as shown in the accompanying drawings.

In testimony whereof I affix my signature in presence of two witnesses.

ANDREW KROUSE.

Witnesses:

F. W. SMITH, Jr.,
J. S. FINCH.
